United States Patent [19]

McCray et al.

US00D330188S

[11] Patent Number: Des. 330,188

[45] Date of Patent: ** Oct. 13, 1992

[54] **COMBINED BATTERY CHARGER AND BATTERY PACK**

[75] Inventors: Leroy, McCray, Chicago; Timothy P. Michel, Naperville; William E. Bale, Des Plaines, all of Ill.

[73] Assignee: Skil Corporation, Chicago, Ill.

[**] Term: 14 Years

[21] Appl. No.: 565,735

[22] Filed: Aug. 10, 1990

[52] U.S. Cl. D13/108

[58] Field of Search D13/107, 108; 320/2, 320/3
